(57) **CLAIM**

The ornamental design of a pin latch, as shown and described.

DESCRIPTION

FIG. 1 is a perspective view of the pin latch of my design; FIG. 2 is a front elevational view thereof;

FIG. 3 is a right side elevational view thereof;

FIG. 4 is a left side elevational view thereof;

FIG. 5 is a sectional view taken along line 5-5 of FIG. 2;

FIG. 6 is a top plan view thereof;

FIG. 7 is a bottom plan view thereof;

FIG. 8 is a sectional view taken along line 8-8 of FIG. 2;

FIG. 9 is a sectional view taken along line 9-9 of FIG. 2;

FIG. 10 is a rear elevational view thereof;

FIG. 11 is a perspective view of the pin latch of FIG. 1 showing the pin in its lock position;

FIG. 12 is a front elevational view of FIG. 11;

FIG. 13 is a right side elevational view of FIG. 11;

FIG. 14 is a left side elevational view of FIG. 11;

FIG. 15 is a sectional view taken along line 15-15 of FIG. 12;

FIG. 16 is a top plan view of FIG. 11;

FIG. 17 is a bottom plan view of FIG. 11;

FIG. 18 is a sectional view taken along line 18-18 of FIG. 12;

FIG. 19 is a sectional view taken along line 19-19 of FIG. 12; and,

FIG. 20 is a rear elevational view of FIG. 11.

1 Claim, 6 Drawing Sheets
